WRIST WATCH BRACELET

George Schmidt, Los Angeles, Calif.

Substituted for abandoned application Serial No.
420,467, November 26, 1941. This application
November 22, 1944, Serial No. 564,639½

2 Claims. (Cl. 224—4)

My invention relates to flexible bands with releasable clasps particularly adapted to be associated with a wrist watch and to releasably embrace the wrist of the wearer.

An object of the invention is to provide a novel band and novel releasable clasp of simple but satisfactory and sturdy construction, affording a maximum of comfort to the wearer, and ease, simplicity and quickness in removing or securing the band from or to the user's wrist.

An object of the invention is to provide a novel strap or band for wrist watches in the nature of a chain thus securing and permitting substantial circulation of air between the band and the skin of the wearer.

Another object of the invention is to provide a novel band formed in part from a standard product which is readily utilized in the flexible band of my invention to secure unique results.

Another object of the invention is to provide a novel releasable clasp of small dimensions but which is readily and easily operated and which securely holds the parts when closed.

Another object of the invention is to provide a novel clasp construction having great strength proportionately to the small size of the clasp and which is practically impossible to inadvertently open.

A still further object of the invention is to provide a novel clasp which when closed provides a particularly neat and attractive appearance free of any protuberances.

A still further object of the invention is to provide a novel band and associated parts that are simple and inexpensive but rugged in construction and easy to manufacture.

The invention resides in the parts and combination of parts more particularly hereinafter described in detail and pointed out in the claims.

Other objects, advantages and features of invention may appear from the accompanying drawing, the subjoined detail description and the appended claims.

The accompanying drawing illustrates the invention in a form I at present deem preferable.

Figure 1 is a face view of a wrist watch showing the attaching loops for the flexible element of the bracelet that is shown in imaginary wrist encircling position.

Figure 2 is an edge view of a wrist watch provided with a flexible band and associated parts constructed in accordance with my invention and showing the clasp in closed position.

Figure 3 is a bottom view of the parts as shown in Figures 1 and 2.

Figure 4 is a view similar to Figure 2 but showing the clasp in released or opened position and one side of the flexible element being partly extended through its respective attaching loop.

Figure 5 is a view similar to Figure 3 but with the clasp members separated to show the co-acting faces thereof.

Figure 6 is a cross-sectional view, on enlarged scale, taken on line 6—6, Figure 2, and looking in the direction of the arrows.

Figure 7 is a cross-sectional view of the clasp taken on line 7—7, Figure 6, and looking in the direction of the arrows.

Figure 8 is a cross-sectional view of one of the 15 clasps, on enlarged scale, taken on line 8—8, Figure 1, and looking in the direction of the arrows.

Flexible bands intended to be worn for considerable periods, such as bands or straps for 20 wrist watches, should, for maximum comfort, provide for free circulation of air to the skin of the wearer in order that the natural moisture which continually reaches the exterior of the skin can evaporate, otherwise this moisture is 25 liable to enter joints in the flexible band, or the material of the band, and clasp, besides causing a feeling of discomfort to the wearer. It follows, therefore, that the clasp itself should be small as practicable without reducing the security of its grip.

The band of a wrist watch, in particular, should have maximum flexibility since the muscles of the wrist are in constant use.

The initial adjustment to adapt a band from 25 stock to the various diameters of different users' wrists should be readily effected, and minor later adjustment provided for, both to accurately initially fit the wearer and to compensate for changes in weight which varies considerable in 40 some people in relatively short periods.

These requirements are met in my invention by the use of a chain preferably of the twisted link type in which the links lie flat. A wrist watch bracelet may be made up from a predetermined length of such chain so as to embrace the average maximum diameter of wrist and the attaching loops may be threaded thereon and the ends of the chain temporarily secured to opposed parts of a separable clasp, so that the prospective user may have the necessary number of links taken from the chain, and the separable clasp parts secured in place to encircle the wrist with the desired degree of snugness. However, should he later wish to have the length of the chain 50 lengthened or shortened to accommodate a vari- 55

ation in wrist diameter, the adjustment can be readily made by releasing one end of the chain from its associated clasp part, and then securing the end of the chain to its clasp member.

The flexible band construction comprises a length of flexible material such as the chain 1, one end of which is secured to one part or base element 2, of a separable clasp, C, that is ultimately arranged at approximately the center of the chain and secured thereto by a pressed out lug 2a. The chain 1 passes through a chain attaching loop 3 through which the chain is freely slideable. A loop 3 is arranged on each side of the clasp element 2 and each loop 3 is provided with a tubular bearing A that is held in position by brazing or soldering thereto a lug B that is pressed out of the underside of loop 3. The bearing A receives the spring bar c of the watch.

A second clasp element 4 which forms a cover or locking member for clasp element 2 is secured to the other end of chain 1 after the chain is threaded through chain attaching loop element 3.

The clasp base element 2 is preferably in the form of a flat hollow rectangular box or housing, but need not necessarily be of such form. Referring to Figures 2, 6, and 7, it will be seen that the surface D of the clasp base 2 next to the wearer's skin, which will be called bottom, is imperforated and a member E having sides 5 and 6 is soldered to bottom D a short distance inwardly from the sides thereof, so as to leave a slight flange F extending therealong. The sides 5 and 6 are slightly bulged intermediate their longitudinal edges, the purpose of which will be hereinafter explained. The ends of member E are provided with centrally disposed depending bracing lugs or sides 7 and 8 that are soldered to bottom member D, providing openings on each side thereof for reception and passage of the chain 1. The top surface of member E is provided with the pressed out lug 2a and with a centrally arranged elongated slot 9 extending in the direction of the chain 1, and an elongated cut out or recess 10 is arranged on the side of the central slot 9 opposite to the pressed out lug 2a and joins one of the apertures in the side. A second struck out lug 11 is provided on the same side of slot 9 as cut out 10 but toward the opposite edge of the top of element E. An aperture 12 is provided in side wall 6 below pressed out lug 2a enabling this lug to be pushed upwardly by inserting a pointed tool and to release the chain 1 from the lug 2a to provide for adjustment, if necessary.

The clasp element 4 is formed like the cover of a box and fits closely over member E of the clasp base 2. The element 4 has its outer top surface and the two longitudinal sides free from projections or apertures, and the sides that extend over the ends of the band are provided with centrally disposed depending members 13 and 14 analogous to, and that overlie the members 7 and 8 when the clasp is closed to position the clasp element longitudinally of the base 2, and the central disposition of the members 13 and 14 relative to its associated clasp element 4 provide cut out portions on each side of such depending members 13, 14 through which strands of chain 1 extend. The depending portion 13, Figures 5 and 7, is preferably of a height such that a finger nail may be easily inserted underneath it when it is desired to release or separate the clasp members, and the other portion 14 is provided with a rounded and extended end to facilitate longitudinal positioning of the part 4 on the base 2 when closing the clasp. Prefer-

ably I form the sides of the clasp parts 2 and 4 with a slight convex curve so that the natural elasticity of the metal holds the part 4 snugly on part 2.

On the underside of the top of element 4 a lug 15 is provided and shaped to snugly fit in aperture or slot 9 formed in the top of element 2. This configuration of the parts acts to resist the forces tending to slide parts 2 and 4 longitudinally over one another. Also on the underside of the top of element 4 of the clasp, a hook 16 (Figure 5) of readily deformed metal is provided and is soldered in position to be received in aperture 10 of element 2. This hook 16 serves to secure one end of the chain to clasp element 4.

In order to enable the flexible member or chain 1 to move freely with respect to the chain attaching loop members 3 which are pivotally secured to the watch, they are formed substantially of D-shape in cross-section (Fig. 4) with the tubular bearings A being soldered to the straight side of the D while the rounded side is preferably shaped in a slight curvature to facilitate sliding of the chain through the loops 3.

In use, the invention will be made in assembled form and detached from the wrist watch or other object with which it is to be associated and the chain 1 will be of predetermined length and secured to the clasp member 2 by the lug or struck out member 11 which, it will be noted, extends in a direction such that a pull on the chain will more securely tend to depress the lug 11 to maintain it in holding position. The chain is then passed through an attaching loop 3 then through the clasp member 2 on the side opposite lug 11 and opening 10 and the lug 2a is not depressed so that the strand of the chain 1 underneath lug 2a may freely pass through clasp member 2. The chain is then passed through a second attaching loop 3 and connected to the hook 16 which is only slightly depressed.

When it is desired to associate the bracelet with a wrist watch, the old strap or bracelet is first removed in the usual manner and then the left-hand attaching loop 3 is secured to the watch by the usual spring bar of the watch, and the chain is then adjusted relative to the watch and the left-hand attaching loop 3 and the clasp C by positioning the watch on one side of the wrist and the clasp in the diametrical opposite side of the wrist and then pulling the chain through clasp 2 underneath lug 2a until the desired position is obtained then the lug 2a will be depressed to maintain the chain in such adjusted position. Then the other attaching loop is secured to the watch and the end of chain connected to clasp member 4 is usually shortened by cutting off the desired number of chain links and then the end link of the chain is secured to hook 16 by depressing the same.

When the clasp members are associated with each other in closed position, the friction of the slight curvature of the sides of the clasp prevent the clasp members from being accidentally separated and the lug 15 fitting into slot 9 helps to keep the parts from being separated longitudinally due to end pull of the chain elements on the clasp and also such lug 15 reduces side strain on the clasp members thereby maintaining the frictional engagement qualities of the clasp for an indefinite period.

It will also be noted that the hook and lug 11 secure the free ends of the chain to the clasp adjacent to each other so that end pull of the chain on the clasp members is further equalized.

I claim:

1. The combination of a flexible watch band and a separable clasp therefor, comprising a length of link chain, a separable clasp comprising a box like clasp part having side openings through which the chain is passed, deformable retaining means carried by and extending within said clasp part to which said chain is secured intermediate its length, a second deformable retaining means arranged within said clasp part to which one end of said chain is secured, and another clasp part fitting closely over said first clasp part and provided with deformable retaining means to which the other end of said chain is secured, the two clasp parts being formed with co-acting surfaces acting to resist relative movement of the clasp parts in vertical and transverse directions, said box like clasp part being provided with an imperforate bottom element, and the remainder of the box like clasp part comprising a top element provided with a retaining aperture, a cut out portion, side elements at the ends of the box like part transverse of the band

5 having said side openings to receive the chain, one of said openings extending into said cut out portion in the top element, and side elements longitudinal of the band, one of which is provided with an aperture to gain access to said deformable retaining means; said second clasp part being adapted to snap over the first clasp part and having an imperforate top and two imperforate sides, the remaining sides comprising 10 depending portions engaging with the sides of the first clasp part intermediate the chain receiving apertures therein.

2. The combination of a flexible band and separable clasp therefor, as set forth in claim 1, having two chain attaching loops one arranged on each side of said clasp to freely slide on said flexible member between said clasp and the end of said flexible member, said attaching loops being provided with means for attachment to a watch, and being formed with a slight curvature on the side opposite the attaching means to facilitate sliding of the flexible band therethrough.

GEORGE SCHMIDT.
